UNITED STATES PATENT OFFICE.

JESSE G. THOMPSON, OF CARBONDALE, PENNSYLVANIA.

INKSTAND.

Specification forming part of Letters Patent No. 40,517, dated November 3, 1863.

To all whom it may concern:

Be it known that I, JESSE G. THOMPSON, of the city of Carbondale, in the county of Luzerne, in the State of Pennsylvania, have invented a new and Improved Inkstand; and I do hereby declare that the following is a full and exact description thereof, reference being had to the accompanying drawings and the letters of reference marked thereon.

The nature of my invention consists in an inkstand from two and a half to four inches in diameter and from one and three-fourths to two inches high, containing an ink-chamber in one side, extending some two thirds of the way across the diameter of the inkstand, and an ink-cup in the top of the inkstand, and on the opposite side from the ink-chamber, and connected with a passage-way for the ink to pass from the bottom of the ink-chamber under the ink-cup and up into the ink-cup near the top, and also a passage-way for the ink to pass out of the ink-cup back into the ink-chamber.

To enable others skilled in the art to make and use my invention, I will proceed to describe its construction and operation.

I construct my inkstand A in any convenient form, with an ink-chamber (shown in the drawings, marked B) with a passage-way, C, coming out of the side of the ink-chamber, at the bottom, and extending up into the ink-

cup D, near the top. The ink-cup D is situated in the upper part of the inkstand, on the opposite side from the ink-chamber, and is provided with another passage-way, E, to convey the ink out of the ink-cup back into the ink-chamber, so that by raising the side of the inkstand in which the ink-chamber is situated, the ink, in seeking its level, will flow through the passage-way C and fill the ink-cup D in the top of the inkstand, where, by letting the inkstand down to a horizontal position, the ink will remain for use. Then by raising the side of the inkstand in which the ink cup is situated the ink will flow through the passage-way E back into the ink-chamber, where it will remain secure from dust and the action of the atmosphere.

The inkstand may be made of metal, glass, or any other suitable material.

What I claim as my invention, and desire to secure by Letters Patent, is—

The placing the ink-chamber B and the ink-cup D in opposite sides of the inkstand, and connecting them with the passage-ways C and E, as herein described, for the purpose set forth.

JESSE G. THOMPSON.
